UNITED STATES PATENT OFFICE.

LINCOLN CHAS. SCHINDLER, OF BRIDGEPORT, CONNECTICUT.

DESIGN FOR A DUST-PAN, SHOVEL, OR SCOOP.

47,170.

Specification for Design.

Patented Mar. 30, 1915.

Application filed December 29, 1914. Serial No. 879,606. Term of patent 7 years.

To all whom it may concern:

Be it known that I, LINCOLN C. SCHINDLER, a citizen of the United States, residing at Bridgeport, in the county of Fairfield and State of Connecticut, have invented a new, original, and ornamental Design for Dust-Pans, Shovels, or Scoops, of which the following is a specification, reference being had to the accompanying drawing, forming part thereof.

Figure 1 is a top plan view of the dust

pan, shovel or scoop showing my new design. Fig. 2 is a side elevation. Fig. 3 is a bottom plan view.

I claim:

The ornamental design for a dust pan, shovel or scoop, as shown.

LINCOLN CHAS. SCHINDLER.

Witnesses:

EDWARD F. ELWOOD,
SHERMAN T. CATE.
